(57) **CLAIM**

The ornamental design for a camouflage spray gun pattern, as shown and described.

DESCRIPTION

FIG. 1 is a camouflage spray gun pattern according to the present invention;

FIG. 2 is a first perspective view of a first embodiment of a spray gun with the camouflage spray gun pattern of FIG. 1; FIG. 3 is a second perspective view of a first embodiment of a spray gun with the camouflage spray gun pattern of FIG. 1; FIG. 4 is a front view of a first embodiment of a spray gun with the camouflage spray gun pattern of FIG. 1; FIG. 5 is a rear view of a first embodiment of a spray gun with the camouflage spray gun pattern of FIG. 1; FIG. 6 is a first side view of a first embodiment of a spray gun with the camouflage spray gun pattern of FIG. 1; FIG. 7 is a second side view of a first embodiment of a spray gun with the camouflage spray gun pattern of FIG. 1; FIG. 8 is a top view of a first embodiment of a spray gun with the camouflage spray gun pattern of FIG. 1; FIG. 9 is a bottom view of a first embodiment of a spray gun with the camouflage spray gun pattern of FIG. 1; FIG. 10 is a first perspective view of a second embodiment of a spray gun with the camouflage spray gun pattern of FIG. 1; FIG. 11 is a second perspective view of a second embodiment of a spray gun with the camouflage spray gun pattern of FIG. 1; FIG. 12 is a front view of a second embodiment of a spray gun with the camouflage spray gun pattern of FIG. 1; FIG. 13 is a rear view of a second embodiment of a spray gun with the camouflage spray gun pattern of FIG. 1; FIG. 14 is a first side view of a second embodiment of a spray gun with the camouflage spray gun pattern of FIG. 1; FIG. 15 is a second side view of a second embodiment of a spray gun with the camouflage spray gun pattern of FIG. 1; FIG. 16 is a top view of a second embodiment of a spray gun with the camouflage spray gun pattern of FIG. 1; and, FIG. 17 is a bottom view of a second embodiment of a spray gun with the camouflage spray gun pattern of FIG. 1. The broken lines defining the spray gun are for illustrative purposes and form no part of the claimed design.
